UNITED STATES PATENT OFFICE.

JOSEPH H. GARTSIDE, OF PHILADELPHIA, PENNSYLVANIA.

MEANS FOR INDICATING BROKEN RAILS.

1,092,986.

Specification of Letters Patent. Patented Apr. 14, 1914.
Application filed March 5, 1912. Serial No. 631,672.

To all whom it may concern:

Be it known that I, JOSEPH H. GARTSIDE, a citizen of the United States, residing at Philadelphia, in the county of Philadelphia and State of Pennsylvania, have invented a certain new and useful Improvement in Means for Indicating Broken Rails, of which the following is a specification.

My invention relates to new and useful improvements in means for indicating broken rails of a railway track, and has for its object to provide an exceedingly simple and effective device of this character which may be readily and quickly applied to either side of a rail and indicate a break in said rail in such a manner that the track walker may readily see the same, permitting him to flag any trains which may be passing over the track thereby preventing great loss of lives and property.

In accomplishing the above named objects, I secure to either side of the web of the rail, a suitable strip of fragile material such as paper. As a train passes over the broken rail, the meeting ends of said rail at the break will be depressed causing said ends to be parted sufficiently to tear the fragile material and this tear may be readily seen by the track walker.

Figure 1, is a plan view of a portion of a track showing a device for placing the fragile material upon the rails, and Fig. 2, an end view thereof.

In carrying out my invention as here embodied, 2 represents the rails of a railway track which are of the ordinary construction having a base 3, a web 4 and a head 5. On either side of the web of both rails is placed a strip of fragile material 6, preferably paper. This strip of paper is of suitable width to extend from the base to the head of the rail and of sufficient length to reach from end to end of each rail with the exception of that portion of the rails covered by fish plates. At

the points where the fish plates are situated, it is necessary to part the strip of fragile material and again fasten it to the next rail, after passing beyond the end of the fish plate. This strip of fragile material may be readily placed upon the rails either by hand or by mechanical means, and I have here described one manner of placing said strip of fragile material upon the rail.

7 denotes a tricycle comprising a triangular frame 8, having journaled therein a

front axle 9, on one end of which is mounted a wheel 10, with two flanges 11, adapted to lie upon either side of the rail. On the opposite end of the axle is mounted another wheel 12 having but one flange 13, which lies upon the inside of the rail. On the rear end of the frame, is mounted a rear axle carrying a flange wheel 10 similar to the front flange wheel 10, the former being 60 in alinement with the latter so that the two will run upon the same rail of the track.

On the frame is mounted a supply disk or wheel 15 having the strip of fragile material, such as paper 16, wound thereon, said strip of fragile material running from the supply disk around the moistening roller 17 then around the pressure roll 18, said pressure roll adapted to force the strip of fragile material against one face of the rail web 75 causing it to stick thereto because of the adhesive material such as cement carried by one face of the fragile material.

In practice it has been found that when a rail is cracked or when partially broken, 80 the ends of the rail at the crack will remain close together, while in their normal position, but when weight is applied to the rail at the point of fracture, said fracture will be enlarged and this happens when a train 85 is passing over the rail at this point. In order to ascertain the point of fracture in a rail, the strip of fragile material is temporarily secured to the rails of that portion of the track which is being inspected and 90 it is only necessary that the fragile material remain in position during the inspection which for five miles of track might be approximately one hour and a half and as the expansion or contraction of a rail during 95 that length of time is infinitesimally small, it becomes unnecessary to compensate for the difference in the co-efficient of the expansion between the steel rail and fragile material.

The railroads at the present time employ track walkers, in an endeavor to locate broken rails and the like, but it being impossible to be at all points of the track at one time and to see said track as the trains 105 pass thereover, said fractures cannot be located, but by the use of my invention, as the trains pass over the broken rail, the fracture will be enlarged causing the fragile material to be torn so that when the track 110 walker passes this point, he will at once notice the tear, permitting him to flag trains

passing over this track, and to notify the proper department, so that the damage may be repaired.

Of course I do not wish to be limited to the exact details of construction and combination of elements as here shown, as these may be varied within the limits of the appended claims, without departing from the spirit of my invention.

Having thus fully described my invention, what I claim as new and useful, is—

1. In combination with the rails of a railway track, strips of paper attached to said rails throughout their lengths.

2. In combination with the rails of a rail-way track, strips of fragile material pasted to the webs of said rails throughout approximately their lengths, whereby a fracture in any of the rails will be visible to casual inspection.

In testimony whereof, I have hereunto affixed my signature in the presence of two subscribing witnesses.

JOSEPH H. GARTSIDE.
